UNITED STATES PATENT OFFICE.

JACOB OBENOUR, OF MARTINSBURG, PENNSYLVANIA.

TRAIN-PIPE CONNECTOR.

1,177,441.

Specification of Letters Patent. Patented Mar. 28, 1916.

Application filed November 9, 1914. Serial No. 871,120.

To all whom it may concern:

Be it known that I, JACOB OBENOUR, a citizen of the United States, residing at Martinsburg, in the county of Blair and State of Pennsylvania, have invented a new and useful Train-Pipe Connector, of which the following is a specification.

The present invention relates to improvements in train pipe connectors, one object of the invention being the provision of mating connecting means carried by abutting ends of the train pipe, which will automatically couple or connect the train pipe simultaneously with the coupling of the cars and which will permit of the automatic disconnection thereof during the uncoupling of the cars.

A further object of the present invention, is the provision of a simple, inexpensive and durable connector which is readily applied to railway cars employing air brake systems and which will properly connect the train line pipes thereof so that there will be no leakage at the joints.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—

Figure 1 is a side elevation showing the two mating members together. Fig. 2 is a section taken on line 2—2 of Fig. 1. Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a section taken on line 6—6 of Fig. 1. Fig. 7 is a section taken on line 7—7 of Fig. 1. Fig. 8 is a section taken on line 8—8 of Fig. 1. Fig. 9 is a detailed longitudinal sectional view through the female connector member showing the position of the male member therewithin.

Referring to the drawings, the numerals 1 and 2 designate the supporting members, which are attached to the body 3 of the car, for the female member of the present connector, the substantially U-shaped frame 5 being connected to these members, one terminal being connected by the single bolt 4, while the opposite terminal is provided with

the two projecting lugs 9 which coöperate with the projections 6 of the member 2 to receive the bolts 7 so that the slots 8 of the lugs 9 will be properly connected thereto 60 so that the member 5 may have a swinging movement imparted thereto and thus accommodate for varying traffic conditions.

An irregular shaped projection or plate 10 is carried upon the forward face of the member 5 to receive a similar shaped flange 12 carried upon the pipe 11, said pipe 11 being mounted through apertures in the terminals of the member 5 and being held against longitudinal movement by means of 70 the plates 12 and 13, the member 10 engaging the plate 12 as indicated in Fig. 4 to prevent rotation of the pipe 11. Disposed in the pipe 11 is a rubber gasket 14 against which the inner end 15 of the male connecting pipe 16 abuts to provide a tight joint.

Carried by the forward end of the pipe 11 is the lower section 17 of the funnel collector, the other section 18 being hingedly connected at 19 to the pipe 11 so as to have 80 movement to and from the lower section 17 to thus accommodate itself to and upon the projecting end of the male connector 16, the coöperating beads 20 and 21 of the funnel members 17 and 18 and the male pipe connector 16 being provided to thus assist in holding the parts against accidental displacement, but permitting the same to be connected and disconnected at the time of the coupling and uncoupling of the cars.

In order to hold the section 18 resiliently toward the section 17 of the funnel collector, strips 22 and 23 are connected as illustrated in Figs. 1 and 5, and have their terminals connected together by the springs 24 to thus 95 resiliently hold the sections toward each other and permit of the proper gripping of the male connector member 16 when assembled as shown in Figs. 1 and 9.

In order to properly mount the male connector member 16 so as to properly accommodate the same to various traffic conditions and thus insure the proper mating of the same with the female member at all times, a U-shaped supporting member 25 is connected to and supported from the car body 26 while fixedly connected to one terminal thereof and projecting therethrough, is the fixed section 27 of the train pipe. This fixed section 27 has one terminal projected within the member 25 and thus fits telescopically within the adjacent end of the male con-

necting pipe 16, which is mounted for limited sliding movement through the opposite terminal of the member 25. A disk 28 is carried by the pipe 27 upon the inner face 5 of one of the terminals of the member 25 and is secured thereto to thus rigidly hold the same in place, while formed upon the inner end of the male connector pipe 16 is a flange 29 which co-operates with the member 28 to hold the spring 30 properly positioned so that the tension of the spring 10 normally holds the male member 16 projected, a second spring 31 being disposed about the pipe 16 within the frame 25 and 15 abutting the opposite side of the flange 29 and the adjacent face of the resiliently supported pipe 27 surrounding and adjusting member 32. This member 32 as clearly illustrated in Figs. 1 and 7 is disposed for sliding movement against one terminal of the member 25 and is held resiliently thereagainst by means of the springs 33, which are connected at 34 to the inner face of one 20 of the terminals of the member 25. Thus 25 this member 32 is normally held upwardly at all times by the springs 33, but is permitted a slight downward movement.

In order to grip the pipe at the opposite side and thus hold it downwardly with a 30 resilient tension, there is pivoted at 35 at the opposite side of the terminal to which the plate 32 is fitted, a swinging pipe engaging member 36, whose opposite terminal is connected by the spring 37 to the lug 38 35 carried by the member 25. This spring 37 exerts a tension to hold the member 36 in position as shown in Fig. 6, that is bearing down upon the upper side of the pipe 16 at the opposite side of the member 25 to the 40 plate 32.

What is claimed is:

1. In a device of the class described, a 45 depending arched hanger embodying forward and rear arms; a pipe section carried by the rear arm; a second pipe section telescoped onto the first specified pipe section and movable vertically in the forward arm; and resilient means assembled with the forward arm and with the second pipe section

for holding the second pipe section centralized.

2. In a device of the class described, a depending arched hanger embodying forward and rear arms; a pipe section carried by the rear arm; a second pipe section telescoped onto the first pipe section and movable vertically in the forward arm; opposed, vertically extended springs, the upper ends of which are assembled with the forward arm; and means for assembling the lower ends of the springs with the second pipe section.

3. In a device of the class described, a depending arched bracket embodying forward and rear arms; a pipe section carried by the rear arm; a second pipe section vertically movable in the forward arm and telescoped onto the first specified pipe section; a collar on the second pipe section; compression springs interposed between the collar and the rear and forward arms; a plate slidable upon the forward arm and receiving the second pipe section; and a supporting spring assembled with the plate and with the forward arm.

4. In a device of the class described, a depending arched bracket embodying forward and rear arms; a pipe section carried by the rear arm; a second pipe section telescoped onto the first specified pipe section and movable vertically in the forward arm; a plate engaged with the forward arm and supporting the second specified pipe section; resilient means for supporting the plate; a swinging member disposed transversely of the second pipe section and bearing thereon; means for pivotally assembling one end of the swinging member with the forward arm; and a spring extended between the other end of the swinging member and the hanger.

In testimony that I claim the foregoing as my own, I have hereto affixed my signature in the presence of two witnesses.

JACOB OBENOUR.
